UNITED STATES PATENT OFFICE.

BYARD F. BROGAN, OF PHILADELPHIA, PENNSYLVANIA.

DESIGN FOR A FINGER RING.

Application filed February 28, 1923. Serial No. 5,328. Term of patent 14 years.

To all whom it may concern:

Be it known that I, BYARD F. BROGAN, a citizen of the United States, residing at Philadelphia, county of Philadelphia, and State of Pennsylvania, have invented a new, original, and ornamental Design for Finger Rings of which the following is a specification, reference being had to the accompanying drawing, forming part thereof.

In the drawing: Figure 1 is a side view of a finger ring in which the new design fragmentarily shown extends throughout the circumference of the ring; and Figure 2 is an edge view of the ring showing my new design.

I claim:

The ornamental design for a finger ring, as shown.

BYARD F. BROGAN.
